UNITED STATES PATENT OFFICE.

JACOB SCHRATWIESER, OF BROOKLYN, NEW YORK.

PLASTER BOARD.

SPECIFICATION forming part of Letters Patent No. 694,111, dated February 25, 1902.

Application filed March 13, 1901. Serial No. 50,981. (No model.)

To all whom it may concern:

Be it known that I, JACOB SCHRATWIESER, a citizen of the United States, residing at the borough of Brooklyn, in the county of Kings, 5 city and State of New York, have invented a certain new and useful Improvement in Plaster Boards, of which the following is a specification.

My invention relates particularly to boards 10 or blocks made of plaster, cement, or other material adapted to be used in constructing walls, ceilings, and other parts of buildings; and its objects are, among others, to provide a board of strong and durable construction 15 which may be readily applied and will afford an advantageous surface for the application of calcimine or other finishing-coat for said walls, &c. It is illustrated in the accompanying drawings referred to, and in which—

20 Figure 1 is a plan view of parts of boards constructed according to my invention with the layers of which the same are composed partly cut away. Fig. 2 is a vertical section of the same on the line 2 2 of Fig. 1. Fig. 3 is 25 a like section of a modification.

A sheet or layer of asbestos, paper, cloth, or other material A, provided with perforations a, constitutes the core or middle layer of the board. This layer, however, may, if 30 desired, be placed upon one side of the other material. The plaster, concrete, or other substance B surrounds the core A and is preferably provided with perforations b, extending through from side to side and also through 35 perforations a of the core, which are in my preferred construction of greater diameter than the perforations b. One or more edges of the board thus formed are corrugated, as shown at b², so that when two boards are placed with 40 their edges against each other an irregular break is provided between them, into which the plaster or other finishing-coat will enter when applied thereon, thus securing the two boards together and on account of the irregularity of the break preventing a crack from being formed in the wall from the shrinking of 45 the same or vibration of the building or from other causes. One surface of the board is also provided with a rough surface, as shown in Fig. 1, for the purpose of assisting the finishing-coat in adhering thereto.

The perforations b¹ (shown in Fig. 3) extend only part way through the board and are not

disposed at a right angle thereto, so that the plaster when it enters the same will form a 55 key and be prevented from becoming loosened and falling off. The perforations b are also for the purpose of holding the plaster, and the perforations a, being of lesser diameter than the perforations b, will allow the plaster on either side of the core to pass therethrough, thus uniting the same on both sides of said core. The perforations b also provide a convenient place for nailing the board when so desired. In order to still further 60 unite the plaster or other material B, additional perforations a' are provided in the core, through which the plaster will pass, and in the modification shown in Fig. 3 the perforations extending through the board B may be 65 entirely omitted, and the perforations a will then serve the purpose simply of uniting the board B on both sides of the core. The size and shape of the perforations are immaterial, and they may be either round, square, oblong, or of other form.

What I claim is—

1. A plaster board comprising layers of different material, each provided with perforations and the material of one layer passing 80 through the perforations of the other.

2. A plaster board comprising two or more layers of different material, provided with perforations, the material and perforations of one layer passing through the perforations 85 of the other.

3. In a plaster board, the combination of layers of different material, and perforations in two or more of the layers, the perforations of one layer being of lesser diameter than 90 those of another.

4. In a plaster board, the combination of layers of different material, and perforations in two or more of the layers, the perforations of one layer being of lesser diameter than 95 those of another and passing therethrough.

5. A plaster board provided with projections and indentations on one or more of its edges, the said projections and indentations being of unequal length.

Signed at the city of New York this 15th day of January, 1901.

JACOB SCHRATWIESER.
